UNITED STATES PATENT OFFICE.

CHARLES BUNGE, OF GENEVA, NEW YORK.

GUN-SIGHT

SPECIFICATION forming part of Letters Patent No. 433,323, dated July 29, 1890.

Application filed April 21, 1890. Serial No. 348,780. (No model.)

To all whom it may concern:

Be it known that I, CHARLES BUNGE, a citizen of the United States, residing at Geneva, in the county of Ontario and State of New York, have invented certain new and useful Improvements in Gun-Sights, of which the following is a specification.

My invention relates to gun-sights; and the invention consists in a novel construction of the sight proper and in means for adjusting the same, as hereinafter more fully described.

Figure 1 is a perspective view of my improved sight attached to a gun. Fig. 2 is a rear face view, and Fig. 3 is a side elevation, 15 with the sight shown in longitudinal section, all being full size.

The object of my invention is to produce a rear sight for guns by which a more accurate aim can be secured and which can be readily 20 adjusted with great accuracy.

The most important feature of the invention is the sight itself. This consists of a tube A, having secured therein three disks a, b, and c, as shown in Fig. 3, one being located at each 25 end and one at the center midway of its length. These disks are made of considerable thickness and of such a diameter as to fit snugly in the bore of the tube, they being simply shoved or forced into place. Each of these 30 disks is provided at its center with a small hole, about the size of those used in the ordinary peep-sights, the three holes being exactly in line, as shown. The central disk b, as shown, is reamed out around the hole on 35 each side, care being taken to have the surface of the conical recess thus formed stand at an angle of forty-five degrees, or practically so. The inner faces of the two end disks a and c are in like manner beveled at the 40 same angle, while their outer faces are made concave on the arc of a circle, as shown in Fig. 3. I would here remark that good results may be produced by making the outer faces of these end disks beveled similar to 45 their inner faces, but not so perfect as by making them circularly concave, and that while both forms come within the scope of my invention I prefer the form described as giving the best results.

For convenience of attachment I reduce the external diameter of the tube A for a little more than half its length and fit upon this

reduced portion another tube or sleeve A', this latter being provided at its rear end with an enlarged concave disk of the usual form 55 to shield the eye from the surrounding light. As shown in Fig. 3, the parts A and A' are provided with screw-threads, with a space left between their abutting shoulders, so that by screwing up the part A' their shoulders are 60 made to clamp the slide D and the leaf B, as shown, there preferably being a collar o arranged to bear against the rear face of the leaf B, as shown in Figs. 1 and 3, though this is not absolutely essential. The result of this 65 construction is that all the rays of light in front of the sight are prevented from reaching the eye, except those which proceed in a straight line from the target or object to and through the holes in the three disks. All 70 other rays of light which enter the hole in the disk a, coming as they must at an angle more or less, will strike the inner wall or surface of the tube A and be reflected at a corresponding angle to the opposite wall, as indicated 75 by the lines in Fig. 3, and will thus be prevented from passing through the hole in the central disk b. The inner wall or surface of the tube A is also blackened, in order to absorb the rays of light which impinge upon it, 80 and thus prevent their reflection, the same as in telescopes.

When an object is viewed through this sight, only a very small field around the object can be seen, and the object or target stands out clear and well defined with a remarkable sharpness of outline. The field of sight being so limited, the slightest movement of the gun is instantly perceived by the person holding it, and this aids to secure greater accuracy.

This sight is designed to be used in connection with a front sight, preferably of the kind known as "globe sights." It may be mounted in any manner desired; but for convenience 95 of support and to enable it to be adjusted with accuracy, and at the same time be capable of being thrown over to one side when it is desired to wipe out the gun-barrel and return the sight to its exact former position, I mount it in the manner shown in the drawings, in which P represents the base-plate, to which 100 is hinged, by the screw g, a short leaf I, arranged to swing to and fro in line with the

barrel of the gun. To this short leaf I, I pivot another leaf B by means of a screw *h*, so that this leaf B can be turned over laterally, as indicated in Fig. 5, its lateral movement being carried to any extent desired. The leaf B is provided on its rear side with a depending arm or lug E, the lower end of which is provided with a rear projection or foot, as shown in Figs. 1 and 3, and directly under this, in the plate P, I insert a screw *l*, as shown in Figs. 2 and 3, on which the foot of lug E will rest when the sight is turned up into position. By adjusting this screw *l* the leaf B can be tipped more or less forward, and thus change the inclination of the sight A, its front end being lowered by throwing the leaf forward and raised by throwing it backward. On the plate P, at the side of the lug E, I make a projection R, as shown in the several figures, and in the side of this projection next to the lug, I inset a screw *f*, as shown in Figs. 1 and 3, against which the side of the lug bears when the leaf B is turned up to the vertical position. This screw serves as a wind-gage, for by turning the screw *f* in or out the leaf with the sight can be adjusted to the right or left to any extent desired, and thus compensate for the effect of the wind on the bullet during its flight, whether the wind be from one or the other side. I prefer to make this lug E in the form of a plate, as shown, as by that means I secure a good bearing on both the front and rear faces of the leaf I, as shown clearly in Fig. 2, and thus insure firmness of position and accuracy of movement. It is obvious that by turning the leaf B the other side foremost the part which bears against the leaf I could be extended down to form the lug or that leaf B and lug E may be made integral by milling out the space for leaf I; but I prefer the plan shown, as the parts can be fitted with great accuracy, and, moreover, the wear can be compensated for by tightening the parts by means of the screw-pivot *h*.

The sight is secured to a slide D, which is moved vertically in the slot of leaf B by a screw C, as shown, these being well known. The reduced portion of tube A is put through a hole in the slide, and then the collar *o* is slipped on and the sleeve A' screwed on, thereby clamping it fast to both the slide and the leaf, thus preventing the slide from being moved until the sleeve is slightly loosened, when the slide with the sight can be raised

or lowered, as desired, after which the sleeve is screwed up again, thereby locking the parts fast.

By this construction I am enabled to produce a sight peculiarly adapted for fine target-shooting and that can be adjusted with great accuracy, both vertically and laterally, that can be made to serve as a wind-gage, thereby avoiding the necessity of adjusting the front sight when once properly set, and that enables the sight to be turned out of the way when it is desired to clean the barrel, and to bring it back to the exact position from which it was moved.

Having thus described my invention, what I claim is—

1. A sight for guns, composed of a tube having two or more perforated disks arranged therein, substantially as shown and described.

2. In combination with a tube A, a central perforated disk having its faces beveled at an angle of forty-five degrees on its opposite sides and two end disks also perforated and having their inner faces beveled at an angle of forty-five degrees and their outer faces made concave on the arc of a circle, as set forth.

3. The combination, in a gun-sight, of the base-plate P, the leaf I, hinged to swing in line with the barrel, and a leaf B, pivoted to the leaf I and arranged to swing at right angles to the movement of leaf I, substantially as shown and described.

4. In combination with the base-plate P, a leaf adapted to support a sight and to swing to and fro in the line of the barrel, and an adjusting-screw *l*, all arranged to operate substantially as and for the purpose set forth.

5. The plate P, provided with a projection R and screw *f*, a leaf B, pivoted to swing laterally, and provided with an arm or lug arranged to strike against said screw when the leaf is turned up into position, substantially as described.

6. In combination with the slide D and hinged leaf B, the tubular sight A, provided with the perforated disks *a*, *b*, and *c*, arranged to operate substantially as shown and described.

In witness whereof I hereunto set my hand in the presence of two witnesses.

CHARLES BUNGE.
